United States Patent Office

Des. 221,405
Patented Aug. 10, 1971

221,405

PEDAL BOAT

Fred Schropfer, 509 Champlain St.,
Fabreville, Quebec, Canada

Filed Apr. 7, 1970, Ser. No. 22,300

Term of patent 14 years

Int. Cl. D12—06

U.S. Cl. D71—1

FIG. 1.

Des. 221,405

PAGE 2

FIG. 2.

FIG. 3.

FIG. 4.

FIG. 1 is an isometric view of the pedal boat,
 FIG. 2 is a plan view thereof, and
 FIGS. 3 and 4 are side and rear elevations, respectively.
 What I claim is:
 The ornamental design for a pedal boat, substantially
 as shown.
